GOLF CLUB

Thomas Pepin, New York, N. Y.

Application April 24, 1934, Serial No. 722,089

1 Claim. (Cl. 273—77)

My invention relates to certain new and useful improvements in golf clubs, and particularly to clubs having enlarged heads such as provided on drivers, brassies, spoons, putters, and the like. It 5 consists in providing means whereby a player is assisted in properly addressing a ball and indicating to the player the proper weight distribution of his body for free pivoting, and it also has the added advantage of greatly assisting a club 10 maker in facing a club initially or thereafter if he is required to modify the face to fit the peculiarities of an individual player. This will be better understood from an examination of the accompanying drawing and a reading of the following 15 specification.

In the drawing—

Fig. 1 is a plan view of the head and a portion of the shaft of a golf club;

Fig. 2 is a front end elevation thereof;

1 represents a club head, 2 the lower end of a shaft, and 3 the striking face of the club head, which in the case of drivers and brassies is almost invariably bulged and laid back to a greater or less degree. 1' represents the bottom or sole 20 line of the head. This line extends straight back from the face 3 to the rear edge of the head. In the proper positioning of the club head in the act of striking the ball, this sole line should travel through in a horizontal plane. If the supporting 25 surface to the rear of the ball were always strictly horizontal, the player could easily face the club properly by permitting it to first rest on the ground in addressing the ball for a stroke, but as such a condition is seldom to be found through 30 the fairways of a course my invention contemplates means to assist the player in properly positioning the club head whether or not the surface to the rear of the ball is level. To that end I provide a line 4 on the top of the head 1 which 35 coincides with a plane coincident with the shaft axis and also at right angles to a plane coincident with the bottom sole line 1'. It is not essential 40 that this line 4 shall always be parallel to the face 3 of the club. The angle of said face may be varied to suit the peculiarities of the individual 45 and when this is the case, in the absence of a guide line similar to that shown herein, it is liable to improperly influence the player and cause him to faultily position the club head in the act 50 of addressing the ball. With the line 4 present, the player may check the position of his club

thereby and be assured that the lower sole line, then invisible, is correctly positioned. Inasmuch as in many cases the player depends upon the appearance of the face of the club to guide him in positioning the head, and inasmuch as in many instances, particularly in the case of drivers and brassies, the club face is bulged, set back, and frequently given what is technically known as a "hook", it follows that the player cannot rely invariably upon the appearance of the club face 10 as a guide. By the use of my guide line positioned as I have explained the player, by concentrating thereon, may be assured that the sole line of the club is properly positioned for the stroke about to be attempted. 15

5 represents a line on the top of the club head at right angles to and crossing the line 4. This line 5 extends from a point directly above the center of the face to the rear of the club. The presence of this line in combination with the line 20 4 will be found to further assist the player in properly positioning the club head since it forms in effect a T-square.

The line 4 is also of great assistance to the golf club maker or professional in the shaping of the 25 face of the club. This line being set back from the striking edge of the club head furnishes a guide so that he may shape the striking face at substantially right angles to the line of flight, or may, indeed, "hook" it to the desired degree if the 30 peculiarities of an individual player call for a face that is hooked more or less. The maker, by referring to the line 4, is greatly assisted in the initial facing of the club or in any refacing that 35 may thereafter be required. The set back guide line 4, positioned substantially as hereinbefore described, therefore performs the double function of greatly assisting the player in executing shots as well as assisting the club maker in the work of 40 facing the club. 45

What I claim is:

A golf club comprising a shaft and a head, having its sole convexly curved to provide a transversely extending sole line, a line formed on said head, which line lies in a plane which contains 50 the shaft axis and which is perpendicular to the transverse sole line of the club head, said second mentioned line being located to the rear of the striking face and spaced substantially therefrom. 55

THOMAS PEPIN.
